DRAINAGE CONTROL FOR WASHING MACHINES

Filed Oct. 20, 1926

INVENTOR.
H. C. Burbidge
BY *George J. Walther*
ATTORNEY

UNITED STATES PATENT OFFICE

HARRY C. BURBRIDGE, OF FRESNO, CALIFORNIA

DRAINAGE CONTROL FOR WASHING MACHINES

Application filed October 20, 1926. Serial No. 142,851.

This invention relates to improvements in washing machines of the type provided with a centrifugal drier. In such machines centrifugal motion is employed to throw the washing water out of the clothes and the latter may then be sprayed with fresh water from the inside for rinsing purposes. As the machines are now constructed, however, this fresh water runs back into the washing water 10 and dilutes it, which reduces the efficiency and increases the cost of the washing operations.

The principal object of my invention is therefore to provide a drainage control 15 structure for such machines so arranged that as the rinsing water is thrown out of the clothes basket by the rotation of the latter, it is caught and discharged from the tub without mingling with the washing water 20 therein.

Any necessary amount of rinsing water may therefore be used without affecting the washing water. On the other hand when the washing water is being rung from the clothes 25 and is running down the sides of the tub, such water may be either returned to the washing water in the tub or discharged from the latter without mingling with such washing water, as may be desired.

30 A further object of the invention is to produce a simple and inexpensive device and yet one which will be exceedingly effective for the purpose for which it is designed.

These objects I accomplish by means of 35 such structure and relative arrangement of parts as will fully appear by a perusal of the following specification and claims.

The figure on the drawing is a fragmentary 40 sectional elevation of a centrifugal drier type washing machine showing my improved drain control means applied thereto.

Referring now more particularly to the characters of reference on the drawings, the 45 numeral 1 denotes the outer container or tub of the machine, having an inner container or basket 2 to receive the clothes 3 to be washed. The basket is turnably mounted in the tub and is supported on a shaft 4 which projects 50 through the bottom of the tub and is driven

in a manner common to such machines, and which forms no part of my invention.

The basket is arranged to be lowered so as to be partially submerged in the washing water 5 in the tub, or to be raised so as to be 55 clear of such water to the position shown in the drawing. This feature also is common practice and I merely make use of the same in carrying out my invention.

Projecting continuously around the interior of the container above the water level is a trough 6, preferably arranged to be somewhat higher on one side of the container than on the other. The side of the basket is provided with perforations 7 as usual, the lower 60 row of perforations being above the inner rim of the trough when the basket is in its raised position.

65 Mounted on the side of the container is a two-way valve of suitable character comprising for instance a casing 8 having a turnable plug 9 therein provided with an opening 10 therethrough. The plug is turned to different positions by a suitable handle member 11. The casing 8 has vertically spaced passages 12 and 13 leading from the periphery of the plug to the lowest point of the trough 6 and to the container 1 below the trough respectively. The casing also has a spout 14 leading therefrom in circumferentially offset 70 relation to the passages 12 and 13. The opening 10 in the plug is so arranged that upon turning the handle communication may be established between the passages 12 and 13 through the plug or between the passage 12 75 and the spout 14 through the plug. The spout may be positioned to discharge directly into a stationary tub or into a drain, or into a reservoir sometimes provided in connection with washing machines.

80 In operation after the clothes have been washed and it is desired to rinse the same, the basket is raised from the washing water and, while being rapidly rotated, fresh water is applied to the clothes in the basket in the usual 85 manner. The valve is set so that the passage 12 is in communication with the spout 14. The revolving motion of the basket causes all the water from the clothes therein to be thrown centrifugally through the perfora- 90 95 100

tions and against the sides of the container, from which said water will run into the trough and then out through the spout, as will be evident. The valve passages are of sufficient size so that they provide ample capacity to carry off all the water from the trough as it accumulates, so that there is no chance of the latter overflowing. The washing water therefore remains undiluted and retains its original heat.

If when wringing the washing water from the clothes it is desired that such water shall be returned to the main body of water in the container, the valve is turned so that the passages 12 and 13 communicate. The water draining into the trough will therefore again pass into the container below the trough instead of out through the spout.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. The combination with a foraminous centrifugally driven clothes basket arranged within a container, of a drainage control means therefor comprising a trough around the inside of the container below the perforations in the basket and above the bottom of the container, the container having an outlet opening from the trough and another from below the trough, a separate outlet member outside the container, and means to allow the two outlets from the container to be put into communication with each other or with the separate outlet member.

2. The combination with a foraminous centrifugally driven clothes basket arranged within a container, of a drainage control means therefor comprising a trough around the inside of the container below the perforations in the basket and above the bottom of the container, the container having an outlet opening from the trough and another from below the trough, a valve casing, a turnable plug therein having a passage therethrough, the casing having separated passages connected with the trough and container outlet openings, a separate outlet passageway from the casing, the plug passageway being arranged so that upon turning the plug communication will be established either between the trough and container outlets or between the trough outlet and the casing outlet.

In testimony whereof I affix my signature.
HARRY C. BURBRIDGE.
